UNITED STATES PATENT OFFICE.

EDWARD MERZINGER, OF PRAGUE, CZECHOSLOVAKIA.

BUTTON.

Application filed October 30, 1923. Serial No. 671,729.

To all whom it may concern:

Be it known that I, EDWARD MERZINGER, a citizen of Czechoslovakia, and resident of Prague, Czechoslovakia, have invented certain new and useful Improvements in Buttons, application of which has been made as follows: Czechoslovakia, Sept. 22, 1922; Germany, Sept. 26, 1922; Great Britain, Oct. 4, 1922, of which the following is a specification.

This invention relates to buttons of the type generally known as non-separable or bachelor's buttons in which the head or button member proper is connected to a base member having a shank which passes through the cloth and is received within the head member and held there so that it cannot be readily withdrawn.

In the construction of the head or button member the head member comprises a dish shaped part in the bottom of which there is an internal annular groove. In this part is placed a disk shaped plate having a central opening with spring tongues which hold the shank of the base member when the two parts are united.

In the manufacture of buttons of this type, it has been found that the plate frequently catches one edge in the groove and is not forced down into position. The head member is thus ruined in manufacture, since the two parts of the button cannot be properly united. The process of manufacture which is carried out by machinery is also interfered with.

An object of my invention is to provide a construction in which the disk like plate member will always move easily to proper position and will therefore always be placed so as to properly grip the pin or shank of the base member.

Another object is to provide a disk member and means for holding it in proper position which are simple and efficient.

Another object is to fashion the base of the head member and the base member so that the cloth will be firmly engaged and there will be no wobbling of the button.

Other objects will be apparent from the following detailed description and the appended claims.

In the drawings:

Figure 1 is a vertical section through the button in position on fabric, taken on the line 1—1 of Figure 2.

Figure 2 is a bottom plan view of the button assembled.

Figure 3 is a section on the line 3—3 of Figure 1.

Figure 4 is a section and Figure 5 a top plan view of the form of construction in which the disk like plate becomes caught at its edge in the annular groove and does not move to proper position.

The button comprises a top or button member proper A and a base member B between which is claimed the fabric C when the button is in use. The base member B is composed of a generally flat member 1 having a depressed central portion surrounded by a ridge 2. A headed pin 3 passes through an opening in the depressed central portion and is fastened to the member 1 in any desired manner. This pin has a more or less pointed end to penetrate the fabric when the button is placed in use.

The top or head member comprises a generally cylindrical part 4, a base 5 with an opening in its center for the passage of the pin 3 and an outwardly flaring flange 6 forming a continuation of the part 4. Within the part 4 and resting on the base 5 is positioned a flat disk 7 having a central opening and provided with slits extending outwardly from said opening to form spring tongues 8. The opening is smaller than the pin 3 and when the parts are assembled as shown in Figure 1, the tongues 8 are forced into the position shown and prevent withdrawal of the pin 3. A generally frustoconical member 9 has a base resting on the outer edge of the disk 7 and its top is engaged by a top piece or cover 10 of appropriate shape having its edge spun over the edge of the part 6. This construction prevents displacement of any of the parts after the device is assembled.

In the construction as shown in Figure 4, the base 5 has an annular groove 11 which is intended to cooperate with the groove 2 of the base member and grip the fabric therebetween. When assembling the parts it is found that the disk frequently catches one edge in the groove 11 as shown in Figure 4 as it is fed in by machinery, and is not properly positioned, thus ruining the button as well as interfering with the operation of the machine. To obviate this difficulty I have made this groove discontinuous forming a number of short depressions 11' as shown in

Figure 3, separated by parts 12 which are continuous with and in the same plane as the base 5.

It is obvious that it will be impossible for 5 the edge of the disk 7 to enter one of the depressions 11' and therefore the disk will always be guided to proper position when fed in by the machinery.

Furthermore, since the depressions 11' 10 which are opposite to the groove 2 in the base member, are not continuous, the two members will grip the fabric more closely and the button will not so easily be able to rotate with reference to the fabric, which 15 movement would result in wear and a general loosening of the button.

Various detail changes may be made without departing from the spirit of the invention which is to be regarded as limited only 20 by the scope of the appended claims.

I claim as my invention:

1. A button comprising head and base members, the base member comprising a disc and a pin adapted to be forced into the head, 25 the head member comprising a body portion the bottom part of which is formed with depressions separated by plane or undepressed portions, a disc having spring fingers adapted to engage the pin and means for holding 30 the disc in place on the bottom of the head member.

2. A button comprising head and base members, the base member having a pin adapted to be forced into the head member, a disc slotted outwardly from its center to 35 form spring fingers to engage said pin and hold it against withdrawal and the bottom of the head member being provided with depressions separated by plane portions which serve to guide the disc into a proper position 40 when being inserted within the head member.

3. A button comprising head and base members, the base member having a plate 45 provided with an annular groove on its inner surface and also having a pin adapted to be forced into the head member, a disc slotted outwardly from its centre to form spring fingers to engage the pin and hold it against withdrawal and the bottom of the head member being provided with depressions which register with the groove in the plate and hold the fabric therebetween, said 50 depressions being separated by plane portions which serve to guide the disc into proper position within the head member.

In testimony whereof, I have hereunto subscribed my name.

EDWARD MERZINGER.
